United States Patent Office

Des. 188,404
Patented July 12, 1960

188,404

APPARATUS FOR APPLYING AND REMOVING MAKE-UP

Antoine Francois Peyron, 4 Rue de Londres,
Paris, France

Filed May 25, 1959, Ser. No. 56,041

Term of patent 14 years

(Cl. D86—10)

FIG-5-

Fig. 1 is a front view of an apparatus for applying and removing make-up showing my new design;

Fig. 2 is a top view thereof;

Fig. 3 is a left side view;

Fig. 4 is a right side view; and

Fig. 5 is a rear view thereof.

The dominant features of my design reside in full lines on the drawing.

I claim:

The ornamental design for an apparatus for applying and removing make-up, as shown and described.
